UNITED STATES PATENT OFFICE.

JAMES MILN SMALL, OF WESTMINSTER, ENGLAND.

APPARATUS FOR PROPELLING ROTARY MOTORS.

No. 823,815.

Specification of Letters Patent.

Patented June 19, 1906.

Application filed August 26, 1903. Serial No. 170,820.

To all whom it may concern:

Be it known that I, JAMES MILN SMALL, civil engineer, a subject of the King of Great Britain and Ireland, residing at No. 17 Victoria street, Westminster, London, England; have invented certain new and useful Apparatus for Propelling Rotary Motors, (for which I have applied for a patent in Great Britain, filed July 28, 1903, Serial No. 16,584,) of which the following is a specification.

This invention relates, first, to apparatus for utilizing the energy derivable from the combustion of a mixture of air and gas or vapor for the propulsion of turbine or other rotary motors in such a manner that the moving part of the motor is subjected to a practically continuous stream of pressure fluid resulting from such combustion, and, secondly, to apparatus adapted to carry out this method in practice.

The apparatus consists, essentially, in the employment of a number of combustion-chambers, in each of which successively a combustible mixture of air and gas is exploded, the products of combustion being then admitted or discharged into a pipe or duct communicating with the motor to be propelled.

In using the apparatus the air is preferably first admitted to the combustion-chamber through a non-return or other suitable valve under pressure and at a temperature sufficiently high to ignite the mixture of air and gas or vapor when the said gas or vapor is subsequently admitted or pumped into the combustion-chamber. Instead of the gas or vapor a sufficient quantity of a suitable oil may be introduced into the combustion-chamber. In this way the motor to be propelled is supplied in succession from each of a number of combustion-chambers with a certain volume of fluid under pressure, and by employing a sufficient number of combustion-chambers and working them at a sufficient rate the variation of pressure of the working fluid on the supply side of the motor can be made as small as may be desired.

In the accompanying drawings, Figure 1 is a section of one of the series of combustion-chambers constructed according to this invention and of the apparatus used for operating the supply and outlet valves of a series of six such chambers. Fig. 2 is a longitudinal section of the valve-operating device or distributing-valve, and Fig. 3 is a diagram-

matic plan view showing a series of six combustion-chambers with connections to a distributing-valve device for such series and with the delivery-pipe and air-supply pipe.

A combustion-chamber *a* communicates with a compressed-air-supply pipe *b* by means of an equilibrium-valve *c* in the valve-chest *c'* and with a pipe *d*, leading to a motor, by means of a similar valve *e* in the valve-chest *e'*.

A cylinder *f*, in which works a double piston *f'*, forms, with the latter, an annulus *g*, which is in communication at one position of the piston with a pipe *g'*, through which oil, gas, or vapor is supplied under pressure, and at another position of the piston with a number of holes *h* in the wall of the cylinder leading to the combustion-chamber.

When the apparatus is intended for use with oil, it is advisable, as shown in Fig. 1, to provide means for expelling into the combustion-chamber, under a high pressure, the charge of oil contained in the annulus between the double piston *f'* and the walls of the cylinder *f*, so as to spray the oil through the holes *h* and secure the admixture of the combustible charge. This may conveniently be done by providing a duct *h'*, leading from the cylinder *f* to a source of air under pressure through a controlling apparatus, as hereinafter described.

The spindles *c² e² f²* of the valves *c e f'* are provided with pistons *c³ e³ f³*, working in cylinders *c⁴ e⁴ f⁴*, each of which is provided with an outlet *c⁵ e⁵ f⁵* to the atmosphere and has an opening at its lower end connected by a pipe *c⁶ e⁶ f⁶* to a chamber in the casing of the distributing-valve. The cylinder *c⁴* is thus connected to the segmental annular chamber *i*, the cylinder *e⁴* with the chamber *k*, and the cylinder *f⁴* with the chamber *l*. All these chambers are situated in the same transverse plane of a casing *m* and have ports *p q r* opening to the interior of the casing. The inside surface of the casing is a cylinder, coaxial with and closely fitting which is a hollow cylinder *n*, which has a number of ports or passages connecting its inner and outer surfaces. Of these passages one, *n'*, connects the interior of the cylinder *n* with an annular chamber *m'* in the casing *m*, this annular chamber being connected permanently to the pipe *b* by the junction-pipe *b'* or to another suitable source of compressed air; and another, *o*, is arranged to connect the inside of the cylinder

successively with the ports p q r as the cylinder n is rotated. The cylinder n may be arranged to be driven by the motor itself, or it may be driven independently thereof by an electric motor n' or other suitable means, the latter arrangement being preferable as providing an independent means of varying the output of the motor.

- When the passage o registers with the port p , compressed air is admitted from the supply-pipe b to the chamber i and the pipe c^6 , leading therefrom. The piston c^3 is therefore raised and the valve c opened, a charge of compressed air being thereby admitted into the combustion-chamber a from the supply-pipe b . When the piston c^3 has traveled beyond the exhaust-passage c^5 and the cylinder n rotated far enough to cut off communication between the chambers i and m' , the piston c^3 will fall, and the valve c will be held closed by the pressure inside the combustion-chamber. The cylinder n next connects, through its ports, the chambers $m' l$, and the piston f^3 is raised to the position in which it is shown in Fig. 1 and with it the charge of oil in the annulus g . When this annulus comes into communication with the discharge-holes h , the piston f^3 at the same time uncovers the end of the duct h' , which opens into the cylinder f^4 , and the expulsion and spraying of the charge of oil is thus facilitated. Further upward movement of the piston f^3 uncovers the discharge-passage f^5 , and the cylinder n , having in the meantime disconnected the chambers $m' l$, the pressure in the cylinder f^4 is reduced to that of the atmosphere, and the piston-valve returns to its lowest position under the pressure of the gases in the combustion-chamber. The continued rotation of the cylinder n connects the chambers $m' k$, and the valve e is opened by air-pressure on the piston e^3 , and the compressed products of combustion resulting from the ignition of the combustible charge in the chamber a is admitted to the pipe d , and thence to the motor, to be driven when the piston e^3 uncovers the passage e^5 , and the cylinder n by its continued rotation closes the communication between chambers $m' k$, the pressure in the cylinder e^4 is reduced to that of the atmosphere, and the valve e returns to the closed position. The valves of a number of similar explosion-chambers are similarly operated by means of the rotary air-pressure valve n , sets of segmental annular chambers $i' k' l' i^2 k^2 l^2$, having ports communicating with the interior of the casing m , being successively connected with the ports $o' o^2$, &c., leading to the interior to the cylinder n , and thence to the compressed-air supply.

The casing n is shown arranged for operating the valves of six combustion-chambers, in which case when compressed air is being admitted to the first combustion-chamber the second chamber will have received its

charge of compressed air and will be awaiting the injection of the oil, the third chamber will be receiving the charge of oil, the fourth will have received the charge of oil and combustion will have taken place, the fifth will be discharging the products of combustion to the turbine, and the sixth will have completed its discharge and will be awaiting the reception of a fresh charge of compressed air. The time occupied by this sequence of operations depends solely upon the speed of rotation of the cylinder n , which can be varied at will.

Preferably the compressor supplying the compressed air to the pipe b , as well as the valve-controlling apparatus, is driven from an independent source of power, such as an electric motor; but this independent motor may be dispensed with, in which case a storage-reservoir for compressed air is provided and the valve-controlling device operated by hand until the turbine is started, when compressor and controlling device will then be driven from the motor.

When gas or vapor is used instead of oil, the oil-cylinder f and piston f' may be replaced by a valve-chest and equilibrium-valve similar to those used for the compressed-air charge and the duct h' may be dispensed with.

The interiors of the combustion-chambers may be lined with a fire-resisting material, and their exteriors, as also the exteriors of the valve-chests, may be surrounded by water-jackets or other means of cooling.

Having thus described the nature of this invention and the best means I know of carrying the same into practical effect, I claim—

1. Apparatus for propelling turbines or other rotary motors, comprising a combustion-chamber provided with valves communicating respectively with a supply of compressed air, a supply of oil, gas, or vapor under pressure, and a discharge-pipe leading to the motor to be driven, and means for successively operating the valves directly by the compressed-air supply.

2. Apparatus for propelling turbines or other rotary motors, comprising a series of combustion-chambers each provided with valves communicating respectively with a supply of compressed air, a supply of oil, gas or vapor under pressure, and a discharge-pipe leading to the motor to be driven, and means for successively operating the valves in each chamber with respect to each other and to the valves in the other chambers of the series directly by the compressed-air supply; substantially as described.

3. Apparatus for propelling turbines or other rotary motors, comprising a series of combustion-chambers each provided with valves communicating respectively with a compressed-air supply, a supply of oil, gas or vapor under pressure; and a discharge-pipe leading to the motor to be driven, and means

by which the individual valves in each of the combustion-chambers are successively operated with respect to each other and corresponding valves in the series of chambers are 5 successively operated with respect to each other directly by the compressed-air supply; substantially as described.

4. Apparatus for propelling turbines or other rotary motors, comprising a combustion-chamber provided with valves communicating respectively with a supply of compressed air, a supply of oil, gas or vapor under pressure, and a discharge-pipe leading to the motor to be driven, pistons attached to 15 each of the valve-rods and working in cylinders, and means for successively connecting each of the cylinders to a supply of compressed air; substantially as described.

5. Apparatus for propelling turbines or 20 other rotary motors, comprising a series of combustion-chambers each provided with valves communicating respectively with a supply of compressed air, a supply of oil, gas or vapor under pressure, and a discharge-pipe leading to the motor to be driven, pistons attached to 25 each of the valve-rods and working in cylinders, and means for successively connecting each of the cylinders to a supply of compressed air; substantially as described.

6. Apparatus for propelling turbines or other rotary motors, comprising a combustion-chamber provided with valves communicating respectively with a supply of compressed air, a supply of oil, gas or vapor under pressure, and a discharge-pipe leading to the motor to be driven, pistons attached to 35 each of the valve-rods and working in cylinders which are in communication with chambers in a valve-casing, and a rotary valve adapted to connect the said chambers success-

sively to a supply of compressed air; substantially as described.

7. Apparatus for propelling turbines or other rotary motors, comprising a series of combustion-chambers each provided with valves communicating respectively with a supply of compressed-air supply, a supply of oil, gas or 45 vapor under pressure, and a discharge-pipe leading to the motor to be driven, pistons attached to each of the valve-rods and working in cylinders which are connected by pipes with chambers in a valve-casing, and a rotary piston adapted to connect each of the chambers to a supply of compressed air, the said chambers being so arranged that the individual valves in each combustion-chamber and also corresponding valves in the series of 50 chambers, are successively operated with respect to each other; substantially as described.

8. In apparatus of the kind herein described a combustion-chamber a valve for 55 the admission of the charge of oil to the combustion-chamber comprising a double piston-valve working in a valve-casing, a second piston attached to the valve-rod and working in a cylinder arranged to be connected with a supply of compressed air, an oil-inlet in the valve-casing, a plurality of small channels in the valve-casing communicating with the combustion-chamber, and a 60 duct which communicates with a supply of 70 compressed air and is uncovered by the pistons when the valve is in position for discharging the oil into the combustion-chamber; substantially as described.

In testimony whereof I have signed my 80 name to this specification in the presence of two subscribing witnesses.
